C. F. Beverly,
Bending Wood,
No 18,379, Patented Oct. 13, 1857.

FIG. 2.

FIG. 1.

UNITED STATES PATENT OFFICE.

CHARLES F. BEVERLY, OF LANCASTER, OHIO.

MACHINE FOR BENDING WOOD.

Specification of Letters Patent No. 18,379, dated October 13, 1857.

To all whom it may concern:

Be it known that I, C. F. BEVERLY, of Lancaster, in the county of Fairfield and State of Ohio, have invented a new and 5 Improved Machine for Bending Wood in Circular Form for the Fellies of Wheels and Analogous Purposes; and I do hereby declare that the following is a full, clear, and exact description of the same, reference 10 being had to the annexed drawings, making a part of this specification, in which—

Figure 1, is a front view of my improvement. Fig. 2, is a transverse vertical section of ditto, taken in the line (x), (x), 15 Fig. 1.

Similar letters of reference indicate corresponding parts in the two figures.

My invention consists in the employment or use of a stationary mold in connection 20 with radial bending arms so arranged and operated that the "stuff" is bent from the center outward, the arms moving simultaneously in opposite directions from the center of the "stuff" and bending the "stuff" so 25 that it will conform to and fit snugly the periphery of the mold.

My invention also consists in a peculiar arrangement of means whereby the "stuff" may be readily adjusted to the machine.

30 To enable those skilled in the art to fully understand and construct my invention I will proceed to describe it.

A represents a base on which two uprights B, B, are placed, the uprights being connected at their upper ends by a cross-tie C. These parts form a frame and it may be constructed of either wood or metal.

40 D represents a vertical bar, the lower end of which is attached to the base A and the upper end to the cross tie C, and E is a block which is permanently secured to said bar D.

F is a mold of semi-circular form, as shown clearly in Fig. 1. This mold is permanently attached to the block E by means 45 of a screw bolt (a) as shown clearly in Fig. 2.

G, G, are two arms, the inner or upper ends of which are pivoted or work on a pin (b) which passes through a block H, said 50 block having its lower end fitted in the upper end of the block E, and the upper end fitted under or behind a bar (c) attached to the cross tie, and into a recess in said tie, the block H, being allowed a certain degree 55 of vertical play. The upper end of the block H has the inner end of a lever (d) fitted

in it. The fulcrum of this lever is at (e) and its outer end is attached by a pin to a vertical rod I, the lower end of which is pivoted to a lever J, having its fulcrum at 60 (f). A vertical rack K is attached to the base A against either of whose teeth the front end of the lever J, may catch.

L is a lever which passes through a slot (g) in the bar D as also does the lever J. 65 To the front end of the lever L a metallic strap M is attached at its center, said strap being sufficiently long to extend fully around the mold F.

N, N, are two segment metal bars which 70 are attached to the cross tie C, and bar D and serves as guides to the arms G, G, the arms being between the mold and segment bars. To the outer end of each arm G there is attached an adjustable block or head (h) 75 in which a roller O, is fitted, and the outer end of each arm has a cord or chain (i) attached to it, the upper ends of which are attached to a windlass or horizontal shaft P provided at one end with a crank Q, said 80 shaft having its bearings (j) attached to the cross-tie C.

The periphery of the mold F, has a flanch (k) attached to it, said flanch projecting from the inner side of the mold and at right angle with its face or periphery. It is designed that the block H, and its arms G, G, shall be sufficiently heavy to fall and be kept at their lowest point by their own gravity when not otherwise acted upon, and it is also designed that the arms G, G, shall fall or descend by their own gravity to a vertical position when not otherwise acted upon. Each side of the block E is grooved 90 vertically to receive the arms, so that they 95 may in connection with their curved form be allowed to assume a vertical position.

The "stuff" R to be bent is previously steamed and the arms G, G, being depressed sufficient room is allowed between the periphery of the mold and the rollers O, O, and strap M, to allow the "stuff" to be readily inserted between them, the ends of the stuff resting on plates (l) provided with stops (m) which serve as guides and enable the operator to place the center of the "stuff" directly under the center of the mold, and also in the same plane with the mold, it being understood that the "stuff" is got out of the proper length. When the "stuff" is adjusted upon the strap M, the front end of the lever J, is depressed by the 100 105 110 115

foot of the operator and the front end of lever L ascends and clamps the "stuff" at its center firmly against the mold F. The crank Q, is then turned and the outer 5 ends of the arms G, G, are moved simultaneously in opposite directions, the rollers O bearing against the "stuff" and bending or pressing it against the periphery of the mold. When the arms G, G, reach a horizontal position they are arrested by stops 13 (n) attached to the tie C, and the ends of the "stuff" are then clamped, the stuff removed from the mold and a new piece adjusted upon the strap, the arms as before 17 stated descending by their own gravity.

The "stuff" in consequence of being operated upon from the center outward is bent with but little power and the work may be done rapidly and well.

18 I would remark that the windlass or shaft P arranged as shown is a simple means of elevating the arms G and will be probably used although other devices may be employed. I would also remark that the mold

F, and the operating parts intimately connected with it may be easily varied as regards size.

Having thus described my invention what I claim as new and desire to secure by Letters Patent, is—

1. The stationary mold F and arms G, G, arranged and operated as shown or in an equivalent way for the purpose of bending the stuff R from its center outward or toward its ends as described.

2. I further claim attaching the arms G, G, to an adjustable block H, operating in connection with the lever L as shown for the purpose of allowing the stuff to be readily inserted or adjusted between the mold F 40 and strap M as described, and also for properly holding the stuff to the mold while the stuff is being acted upon by the rollers of the arms G, G.

CHARLES F. BEVERLY.
